UNITED STATES PATENT OFFICE

OLIVER NYE, OF TOLEDO, OHIO

DESIGN FOR A KITE

Application filed April 6, 1931. Serial No. 39,379. Term of patent 3½ years.

To all whom it may concern:

Be it known that I, OLIVER NYE, a citizen of the United States, and resident of Toledo, county of Lucas, and State of Ohio, have invented a new, original, and ornamental Design for a Kite, of which the following is a specification, reference being had to the accompanying drawings, forming a part thereof.

In the drawings,
Fig. 1 is a plan view, and
Fig. 2 is an elevation of my new design.
I claim:
The ornamental design for a kite as shown.
In testimony whereof I have hereunto signed my name to this specification.

OLIVER NYE.
